UNITED STATES PATENT OFFICE.

WM. VAN ANDEN, OF POUGHKEEPSIE, NEW YORK.

IMPROVEMENT IN CENTRIFUGAL SUGAR-DRAINERS.

Specification forming part of Letters Patent No. 8,156, dated June 10, 1851.

To all whom it may concern:

Be it known that I, WILLIAM VAN ANDEN, of Poughkeepsie, in the county of Dutchess and State of New York, have invented a new and useful Improvement in Machinery for Refining Sugar, Salt, or other Articles by Centrifugal Force, of which the following is a full and exact description, reference being had to the annexed drawings, making a part of this specification, in which—

Figure 1 is a side view or isometrical perspective. Fig. 2 is a vertical section through the center. Fig. 3 is a perspective view of the cylinders and elevator at its highest point. Fig. 4 is a perspective view of the elevator, showing the plow, the same letters referring to the same parts in the different drawings.

B, Figs. 1, 2, 3, is a cylindrical or tub-shaped vessel, resting in a vertical position on the frame A, with a central aperture in the bottom to admit of the passage of the screw-shaft I, which is joined to the elevator D, and of the hollow shaft or nut G, which is connected with the strainer C. About this aperture a lip, v, Fig. 2, is turned up from the bottom, so as to form a shallow trough or gutter with the circumference of the cylinder. A tube, f, Fig. 2, leads from this gutter for the purpose of carrying off the fluids which may percolate through the strainer, a sufficient space intervening between this and the outer cylinder to allow of their free descent into the gutter at the bottom of the latter.

C, Figs. 1, 2, 3, is a hollow metallic cylinder resting within and in a corresponding position with the former on the top of the hollow shaft or nut G, to which it is attached. At its upper and lower extremities it has flanges h h', Fig. 2, between which extend vertical ribs i i, Fig. 3, at proper intervals to brace and support the spiral slats j j j, Fig. 3. These slats are formed by turning on the inside of the cylinder, from top to bottom, a screw-thread, the groove or slit between the threads extending through its entire thickness, with the exception of the flanges and ribs, which thus form a frame-work about the strainer. From the upper flange a rim, g, Figs. 1, 2, 3, projects over the edge of the outer cylinder to prevent the substance refined from falling into it as it is being discharged from strainer.

G, Fig. 2, is a hollow shaft or nut in a vertical position on the screw-shaft I, having jour-

nals t t resting in bearings u u' on the frame A. At its upper extremity, and within the outer cylinder, is a wheel-shaped expansion, w, Fig. 2, a section of which, with the shaft, presents a T shape, which forms the floor of the strainer, the floor w resting a small distance above the lip v, and the ring g in like manner above the edge of the outer cylinder, B.

H, Fig. 2, is a wheel near the middle of the nut G, between the journals t t', around which passes a belt, a, Figs. 1, 2. In the lower portion of the nut a female screw, k, Fig. 2, the thread of which is of the same pitch or inclination as the thread of the strainer before mentioned, is cut to receive a corresponding screw on the shaft I when the elevator is required to be raised. The elevator D, Figs. 1, 2, 3, 4, which is joined to the upper part of the shaft I, is a circular disk of metal of the same diameter as the cylinder C, on the circumference of which a screw is cut to match the spiral groove or female screw in the strainer, in which it is made to rise and fall by the screw-shaft in a manner subsequently explained. When down, in which position it remains during the first or refining stage of the process, it forms a second or false bottom to the strainer, with which it revolves. The upper thread of the screw on the elevator is cut off in such a way that the end presents a prominent point or plow, e, Fig. 4, which, as the elevator ascends in the act of discharging, follows the groove in the strainer, and, fitting it accurately, removes whatever is contained therein. A perforated cylinder or cup, E, Figs. 1, 2, 3, about two-thirds the diameter of the strainer, with openings of sufficient size to allow of the free transmission of the substance to be refined, rises from the upper face of the elevator, supporting at its top a rim, F, Figs. 1, 2, 3, wide enough to cover the space between it and the strainer, and when the elevator is down the outer edge of this rim rests upon the inner edge of the rim of the strainer, to which it acts as a cover, preventing its contents, in the rapid revolution to which they are subjected, from flying out over the top. In the center, over the upper end of the shaft, is a cone, d, Figs. 1, 2, 3, the object of which is, when the machine is being charged, to prevent the ingredients from lodging on the center. The vertical screw-shaft I, Fig. 2, the upper extremity of which, passing through the nut G, sup-

ports the elevator, the lower end running in a bearing, u'' , of the frame A, has upon its middle portion a screw, l, cut to match the female screw of the hollow shaft or nut G, its thread also corresponding in pitch with that of the elevator D. Below two grooves, $m m'$, encircle the shaft, and between them is a vertical groove, n.

K and L are similar pulleys revolving upon the shaft, but kept in position by pins P P' piercing each, and entering, respectively, the circular grooves $m m'$ of the shaft. The upper pulley, K, is greater, and the lower, L, is equal in diameter with the wheel H on the nut G. The upper pulley, K, has on its under side a recess or slot, q, in the hub, and the lower pulley, L, has on its upper side a similar slot, q' . Between the pulleys K and L on the shaft I is a clutch, M, with a feather, r, projecting above and below in the vertical groove n, so that while the clutch revolves with it is at the same time to a certain extent susceptible of a vertical motion upon the shaft. Around the clutch, in a groove, o, is coupled a strap, N, with long arms s s', Fig. 1, resting on the stops O O'. These stops are attached to the sides of the frame A in reversed positions, so as to admit of a partial rotation of the arms as they are moved up the inclination from the bottom, when the feather r is required to enter the slot q of the upper pulley, K. The driving-shaft Q, Figs. 1, 2, running in bearings x x' at the top and bottom of the iron brace-frame P, has on it two pulleys, an upper and smaller, R, a lower and larger, S. From the upper driving-pulley a belt, a, passes around the wheel H, by which power is transmitted to the hollow shaft, and a rotary motion is communicated to the strainer. From the lower driving-pulley two belts, b c, pass, respectively, around the pulleys K and L, causing them to revolve with unequal velocities, either independently on or alternately with the screw-shaft, as may be required.

T, Figs. 1, 2, is a crank attached to the upper extremity of the driving-shaft by means of which the machine is set in motion. The pulleys or band-wheels K L have flanges at top and bottom to retain the belts b c as they are carried up and down by the shaft I, and the driving-pulley S is wide enough to allow of the belts being carried up and down upon it.

z, Figs. 1, 2, is a floor to which the frames A P are fastened.

The operation of the machine is as follows: The strainer C is set in rapid motion by means of the belt a, passing from the driving-pulley R to the wheel H on the hollow shaft G. Since the pulleys K and L are now loose on the screw-shaft I, the elevator D, being at its lowest point, rests on or near the bottom of the strainer, and revolves with it. The moist sugar or other article operated on is now introduced into the inner cylinder or cup, E, through the apertures of which it is projected by the centrifugal force, and lodges against the inner surface of the strainer, the rim F

preventing its escape over the top. The linear openings between the slats j j j are sufficiently narrow to arrest the solid or crystallized portion of the ingredients, and at the same time will admit of the percolation of the fluid portions which are thrown out against the inner surface of the outer cylinder, B, by the centrifugal force, whence they fall into the trough at its bottom and flow out at the pipe f. When the refining process has been carried to the required extent and we wish to remove the contents from the strainer, the arms s of the strap N are drawn up by hand on the inclination at the bottom of the stop O, which causes the clutch M to rise, and brings the feather r, which slides in the vertical groove n on the shaft I, into contact with the under surface of the hub of pulley K, and causes it to enter the slot q, where it is held by the pressure exerted between the side of the slot and the side of the vertical groove, so that the pulley is made to revolve with the shaft. Now, the pulley K, being larger in proportion to the wheel H than the driving-pulley S is to the driving-pulley R, the pulley K revolves slower than the wheel H. Consequently the screw-shaft revolves slower than the hollow shaft and the elevator slower than the strainer. The effect of this inequality between the velocity of the screw-shaft and that of the hollow shaft is equivalent to the former remaining stationary and the latter revolving around it with a velocity equal to the difference between the two; but as the latter is fixed in its position, as the screw l enters the screw u the former rises, carrying with it the pulleys K L and the clutch M, the lower end of the screw-shaft sliding in the bearing u'' at the bottom of the frame A. The elevator, being attached to the upper end of the shaft I, is also made to rise in the strainer. The plow e, following the spiral groove, dislodges its contents, which are thrown out over the rim of the strainer, the rim F of the central cup having been carried up with the elevator. Thus the machine at the same time discharges itself and clears the strainer while it is kept in motion. When the elevator has risen nearly to the top of the strainer, the arms s s' of the strap N, which is carried up with the clutch, strike the upper part of the stop O, so that the pulley K rises away from the clutch and runs loose on the shaft as the elevator reaches the surface, the feather r at that point being drawn from the slot q. The clutch now falls upon the lower pulley, the feather enters the slot q' on its upper side, so that the pulley L is now made to revolve with the shaft. Now, the pulley L is equal in diameter to the wheel H, but the driving-pulley S greater than the driving-pulley R. Therefore the velocity of the pulley L is greater than that of the wheel H, that of the inner than that of the outer shaft, and the velocity of the elevator greater than that of the strainer. The effect of the unequal velocities of the inner and outer shafts in this case is equivalent to latter remaining stationary and the former revolving in it with a ve-

locity equal to the difference between the two, or to the former remaining stationary and the latter revolving around it with the same velocity, but in the opposite direction. The screw-shaft therefore descends, carrying with it, as in the former case, the pulleys and clutch until the arms of the strap again reach the bottom of the stop, when the feather is released, as before, from the slot q' , and the pulley L again runs loose on the shaft. The elevator, at the same time having retraced its course, again rests at the bottom of the strainer, the rim F on its top, and the machine is ready for a fresh charge and a repetition of the process. The elevator may also be made to discharge and cleanse a strainer with vertical or inclined grooves in like manner by allowing it to be

free to rotate on the end of the shaft, and adapting a plow to each groove.

What I claim as my invention, for which I desire to secure Letters Patent, is—

The contrivance for discharging and at the same time cleansing the strainer while in motion by means of an elevator rising in a spiral groove, substantially as described, or by an elevator rising in vertical or inclined grooves, which is essentially the same.

In witness whereof I have hereunto subscribed my name the 8th day of April, 1851.

WILLIAM VAN ANDEN.
